Primary Examiner — Khawaja Anwar*Assistant Examiner* — Mojtaba Tehrani(57) **CLAIM**

The ornamental design for an archery bow riser, as shown and described.

DESCRIPTION

FIG. 1 is a right-rear angled view of an archery bow riser in an environment of use, showing my new design;

FIG. 2 is a right-rear angled view thereof;

FIG. 3 is a right-side view thereof;

FIG. 4 is a left-side view thereof;

FIG. 5 is a front view thereof;

FIG. 6 is a back view thereof;

FIG. 7 is a top view thereof; and,

FIG. 8 is a bottom view thereof.

The dash-dot broken lines in the Figures depict boundaries of the claimed design; the dash-dot-dot lines depict unclaimed portions of the bow only. The broken lines form no part of the claimed design.

1 Claim, 3 Drawing Sheets---
